INSTRUMENT CASE

William F. Brecht, Toledo, Ohio, assignor, by
mesne assignments, to Plaskon Company, In-
corporated, a corporation of Delaware

Application February 17, 1936, Serial No. 64,417

3 Claims. (Cl. 217—69)

In the construction of cases for housing instruments or mechanisms, such as meters, radios, balances, weighing scales, coffee mills, and so forth, and other articles of manufacture, it was generally customary to assemble separate parts, such as ends, sides, covers, bottoms, etc., into a unit by overlapping portions of the parts and when the cases were large with the aid of a frame. This required the use of a relatively large number of screws, rivets or other fastening means which are unsightly and interfere with the efficient cleansing of such cases which furthermore were not very rigid. To overcome these objections, such cases have been molded in one piece from plastic materials by die casting in the case of metals or hot pressing in the case of molding materials such as synthetic resins made by the condensation of urea and formaldehyde or phenol and formaldehyde. Cases so made are highly satisfactory but have the disadvantage of requiring bulky and costly molds even for medium sized articles.

I have found that it is possible to construct even very large cases, or other articles of manufacture, which are assembled from smaller molded parts thus materially decreasing size and costs of molds and eliminating other objectionable features heretofore encountered; therefore, one of the principal objects of my invention is the provision of improved means whereby shaped parts may be assembled into a rigid unit in which the parts are incapable of shifting after assembly.

Another object is the provision of improved means whereby all screws, used in assembling such cases, are concealed in the interior.

Still another object is the provision of improved means for effectively concealing the joints formed by engaging edges of the parts entering the assembly of the case.

Other objects and advantages will be apparent from the following description in which reference is had to the accompanying drawing, wherein similar reference numerals refer to similar parts throughout the several views.

Referring to the drawing:—

Figure I is a perspective view of an assembled weighing scale case which embodies my invention.

Figure II is an enlarged, fragmentary view of joint securing and concealing means; and,

Figure III is a cross sectional view substantially along the line III—III of Figure II.

Referring to the drawing in detail:—

The case 4 which I have shown by way of illustration comprises a front part or section 5 and a back part or section 6, engaging edges 7

and 8 of the front and back sections 5 and 6 respectively, jut outwardly and form raised surfaces 9 and 10 having sloping shoulders 11 and 12 which are adapted to be embraced by correspondingly sloped flanges of a cover strip 13, 5 which may be a strip rolled from stainless steel, or other metal or material, cut to length and bent to conform to the contour of the casing sections, or this cover strip may be molded to conform to the contours of the housing sections. 10 Bosses 14, either welded to, if the strip is metal or molded integrally, project through apertures 15 formed by coincident cut-out portions in the jutting edges of the front and back sections 5 and 6 of the case 4. Screws 16 threaded into the 15 bosses 14 in cooperation with washers 17 draw the flanges of the strip 13 tightly against the shoulders 11 and 12 of the casing sections thus efficiently locking the section together. The 20 slopes of the shoulders and of the flanges of the strip 13 may be so calculated and designed that the edges of the section are tightly drawn together by a wedging action making the assembly 25 a very rigid unit. The strip 13, however, serves another purpose, that of improving appearance by concealing the joint.

Since the bosses 14 enter the apertures 15 with clearance on all sides, means must be provided to prevent relative shifting of the sections before and while the screws 16 are being tightened. To 30 accomplish this I provide one or more projecting tongues 18 on one of the sections 6, each of which are adapted to snugly enter notches 19 molded or machined in proper position in the other section 5.

While the preferred embodiment described in the foregoing is a case adapted to house a mechanism the invention may be generally applied in the assembly of parts to form large surfaces such as wall paneling or containers too 40 large or uneconomical to mold in one piece; therefore, it is to be understood that the invention is susceptible to variation, modification and change within the spirit and scope of the subjoined claims.

Having described my invention, I claim:—

1. In an assembled article, in combination, a plurality of wall parts, each of said parts having an edge adapted to align with and engage an edge of another of said parts, projecting portions 50 adjacent and parallel to said engaging edges, a channel strip adapted to engage said projecting portions of two of said plurality of parts to prevent their disengagement and screws projecting through said parts and entering sockets in said 55

channel strip to lock said parts and said channel strip into a unit, said sockets having closed bottoms and being invisible from the exterior side of said strip.

5 2. In an article of manufacture, in combination, a plurality of molded wall parts, an edge of each of said parts being adapted to be joined to an edge of another of said parts, a projecting portion adjacent each of said joined edges, an 10 aperture formed by notches in said edges, a formed strip-like member having flanges adapted to embrace said projecting portion of each of said plurality of molded parts, a boss fixed to said strip and positioned intermediate the flanges of 15 said strip adapted to project into said aperture, a plate overlying said aperture and a screw projecting from said plate threaded into a socket in

said boss for locking said strip rigidly to said plurality of molded parts.

3. In an article of manufacture, in combination, a plurality of molded wall parts, an edge of each of said parts being adapted to be joined to an edge of another of said parts, a beveled flange projecting outwardly adjacent each of said joined edges, a combined clamping and covering member overlying said joined edges and said beveled flanges, said combined covering and clamping member also having beveled flanges which engage the beveled flanges on said wall parts and means for drawing the flanges of said covering and clamping member into clamping engagement with the flanges of said wall parts. 10 15

WILLIAM F. BRECHT.
